(57) CLAIM

The ornamental design for a split yoke for a dental X-ray unit, substantially as shown and described.

DESCRIPTION

FIG. 1 is a perspective view of an embodiment of our ornamental design for a split yoke for a dental X-ray unit, including, in phantom, the entire dental X-ray unit;

FIG. 2 is a perspective view of an embodiment of our ornamental design for a split yoke for a dental X-ray unit; FIG. 3 is a front elevational view thereof, the rear elevational view being a mirror image thereof;

FIG. 4 is a side elevational view thereof;

FIG. 5 is a side elevational view thereof, from the opposite side;

FIG. 6 is a top plan view thereof; and,

FIG. 7 is a bottom plan view thereof.

The portions shown in phantom or broken lines in FIG. 1 form no part of the claimed design and are included only for the purpose of illustrating an environment.
